CLAIM

(21) Appl. No.: **29/327,522**

The ornamental design for a combination vacuum pump and alternator mount, as shown and described.

(22) Filed: **Nov. 7, 2008**

DESCRIPTION

(51) **LOC (9) Cl.** **15-01**

FIG. 1 is a perspective view of a combination vacuum pump and alternator mount in accordance with the new design;

(52) **U.S. Cl.** **D15/5**

FIG. 2 is a top view thereof;

(58) **Field of Classification Search** D15/1-5,

FIG. 3 is a right side view thereof;

D15/7; 123/198 R, 198 C, 195 A, 41.44,

FIG. 4 is a bottom view thereof;

123/647

FIG. 5 is a left side view thereof;

See application file for complete search history.

FIG. 6 is a rear view thereof; and,

FIG. 7 is a front view thereof.

The broken lines represent the oval of the combination vacuum pump and alternator mount, which forms no part of the claimed design.
